PUMPS FOR AERATING MINNOW BUCKETS

Earl L. Munch, 2639 Wilton Ave.,
Dallas, Tex. 75211

Filed July 13, 1966, Ser. No. 3,069

Term of patent 14 years

(Cl. D91—1)

FIG. I is an elevational view of a pump for aerating minnow buckets showing my new design;

FIG. II is a side elevational view taken from the opposite side of FIG. I;

FIG. III is a side elevational view taken from the right side of FIG. I;

FIG. IV is a top plan view; and

FIG. V is a bottom plan view.

I claim:

The ornamental design for pumps for aerating minnow buckets, substantially as shown.
